GEORGE H. KELLINGTON AND WALTER A. PRESCOTT, OF DECATUR, ILLINOIS.

WATER-CARBONATOR.

1,280,490.

Specification of Letters Patent.

Patented Oct. 1, 1918.

Application filed March 26, 1917, Serial No. 157,460. Renewed July 11, 1918. Serial No. 244,737.

To all whom it may concern:

Be it known that we, GEORGE H. KELLINGTON and WALTER A. PRESCOTT, citizens of the United States, residing at Decatur, in the 5 county of Macon and State of Illinois, have invented certain new and useful Improvements in Water-Carbonators, of which the following is a specification.

This invention relates to an improvement 10 in water carbonators, and more particularly to that type of device as shown in our co-pending application Serial Number 73,744, filed January 22, 1916, and over which the present structure is an improvement.

15 An object of our invention is to provide a device of the character described which has the parts thereof so constructed and arranged that the water and gas are taken into the carbonator through passages opening at spaced apart points and the gas is delivered to exert impelling force upon the water to increase the head at which the same moves, thereby furnishing a motive power sufficient to give the necessary pressure of 20 25 carbonated water at the draft arm or other point of discharge.

A further object lies in so arranging the parts that the gas inlet port is at all times water sealed, and in providing a double 30 valve which controls the supply of both water and gas simultaneously, the valve being so arranged that it is automatically unseated by the pressure of the fluids thereagainst when the pressure within the carbonator is released through opening of the 35 check valve in the draft arm.

With the above and other objects in view which will be in part described and in part understood from the specification, drawings, 40 and claims, our invention consists in certain novel features of construction and combination of parts which will be hereinafter more fully set forth.

In the drawings:—

45 Figure 1 is a view in elevation of a carbonator constructed after the manner of our invention; and,

Fig. 2 is a vertical sectional view through the structure to disclose the arrangement 50 and mounting of the parts.

The base block 1 is enlarged at one end and is bored out to form the water chamber as shown at 2, this enlarged portion of the base block being externally screw threaded around the open end of the water chamber.

A substantially bell-shaped casing 3 is constructed to be fitted to the base block by being set upon the external screw threads thereof to provide a mixing chamber 4 into which the water chamber opens. The casing 3 has a passage 5 leading therefrom to provide connection from the mixing chamber 4 to the draft arm of the fountain, and the base block 1 has the water inlet passage 6 and the gas inlet passage 7 extending laterally thereinto, nipples formed around the passages and extending from the base block being externally screw threaded to provide for suitable connection to the sources of water and gas supply.

The water inlet passage 6 preferably communicates with the water chamber 2 substantially at the side thereof and the gas inlet passage 7 connects with a gas supply passage 8, which is arranged to inject the 75 gas into the water chamber substantially at the center thereof and in a line of flow toward the end of the water chamber opening into the mixing chamber 4. The bore forming the gas supply passage 8 is continued 80 through the base block 1 and the internal screw threading is provided as at 9, a valve stem 10 being externally screw threaded to be turned into the threaded bore of the block 1 and to be adjusted with respect to the seat 85 11 to thus vary and regulate or entirely cut off the supply of gas through the passage 8 into the water chamber. The valve stem 10 has a suitable handle 12 provided thereon for manual manipulation of the stem, and 90 it is also perhaps desirable that a packing gland 13 be provided around the stem to establish a fluid tight joint. The block 1 is recessed around the passage 8 to leave a 95 nipple outstanding with the passage 8 opening therethrough and the inner wall of the recessed formation is internally screw threaded, a sleeve 14 being turned into this screw threaded recess to form a gas chamber through which the gas is conducted previous to discharge into the water chamber 2. This sleeve 14 is made of such length that it is carried somewhat below the water inlet passage 6 and thus even when the check valve of the fountain is closed and the water and gas are held under pressure, the outlet 105 for the gas will be water sealed.

A hub portion 15 is disposed at the open end of the water chamber 3, and the passage 5 forming an outlet from the mixing cham- 110

ber 4 is divided where it communicates with the chamber to leave a bearing portion 16, the opening of this bearing portion 16 and the opening of the hub 15 being disposed substantially in alignment. A valve 17 has a stem 18 extending from one side thereof to be received slidably through the opening of the hub portion 15 and a stem 19 extends from the opposite side to have a sliding fit 10 through the bearing portion 16, the valve being thus mounted in such relation that it is disposed over the open end of the water chamber 2. A suitable packing as indicated at 20 is provided in the valve and thus as 15 the spring 21 mounted around the stem 19 normally exerts bearing pressure to close the valve 17 over the open end of the water chamber 2, this packing will establish a fluid-tight closure of the water chamber and 20 the escape of water into the mixing chamber will be precluded. As has been stated, the gas supply passage 8 opens through a nipple formation into the sleeve 14, and the 25 end of the stem 18 is externally screw threaded and has a packing washer 22 carried thereby, this stem 18 being of such length that as the valve 17 is closed against the seat provided around the opening of the water chamber, the packing washer 22 will 30 close over the discharge end of the gas supply passage 8.

The stem 19 has a bearing 23 provided thereon adjacent the valve 17 and a turbine mixer 24 is revolvably mounted on this bearing, a washer 25 being provided to hold the mixer in the proper position. It is preferable that the turbine mixer 24 be constructed substantially after the manner of a fan or a fluid motor wheel and that the blades be 40 made of such length that they extend beyond the periphery of the valve 17.

In the use of the carbonator as described, the structure will be mounted in the position shown in the drawings or under some 45 conditions might be reversed so that the discharge passage 5 will be disposed upwardly, this depending somewhat upon the conditions of use; the connections will be made from the sources of water and gas supply and a suitable connection will be established to the fountain. If desired, a cut off and control valve can be provided in the water supply line to permit variation of the amount of water supplied but under ordinary 50 working conditions proper regulation can be accomplished through variations in the gas supply, these being made through manipulation of the valve 10. When the valve 10 has been set to give the proper supply of gas through the passage 8, it will be understood that this same proportionate supply of gas and water will be maintained until the parts are again adjusted. As long as the valve of the fountain remains closed, 55 the pressure upon the forward and back

sides of the valve 17 will be equalized and the spring 21 will exert pressure against the valve structure to cause the packing rings or washers 20 and 22 to be seated over the open end of the water chamber 2 and the 70 discharge end of the gas supply passage 8, in which relation the parts will be maintained until the pressure in the mixing chamber 4 is reduced through opening of the valve at the fountain. Immediately the 75 pressure is reduced within the mixing chamber, the water within the water chamber and the gas within the supply passage 8 will exert sufficient pressure upon the valve structure that it will be unseated against the 80 resilient closing pressure exerted by the spring 21 and then the gas will flow through the sleeve 14 to escape into the volume of water in the water chamber and these two volumes will pass through the open end of the 85 water chamber and around the valve 17 over the peripheral edge thereof to impact against the blades of the turbine mixer 24. The flow of the fluid against the blades of the mixer will cause the same to be revolved and thus an agitation of the fluid contents of the mixing chamber and of the inflowing fluid will be accomplished to secure the proper intermixing of the water and gas. Following the flow of the fluids into the 90 mixing chamber and the intermixing of the same by the action of the mixer 24, the carbonated water will flow through the passage 5 and then to the draft arm of the fountain. As the gas is discharged from 95 the mouth of the sleeve 14 into the volume of the water adjacent the opening from the water chamber, the pressure of the gas will increase the head of the water and in consequence the necessary pressure of the carbonated water is more efficiently maintained at 100 the point of discharge. When the valve of the draft arm is again closed, the pressure within the mixing chamber and the water chamber will be equalized and the spring 21 105 will again act to close the valve 17 to cut off communication from the water chamber to the mixing chamber and to also close the open end of the gas supply passage 8.

From the foregoing it will be seen that we 110 have provided a water carbonator which takes advantage of the principle of operation as set forth in the co-pending application but which is so arranged that the gas discharge is from a center into the body of 115 water entirely surrounding the gas opening and is so arranged that by the superior pressure of the gas, the water and carbonated water is driven through in a greater volume when the pressure is removed from the valve 120 closing the water chamber, to thus aid in securing and maintaining the necessary pressure of carbonated water at the points of discharge. Also it will be noted that through 125 the attainment of the higher pressure a more 130

efficient mixing is accomplished by more rapid operation of the turbine mixer, and that the arrangement of the valve structure leaves the gas and water valves on different levels making it possible to have the gas inlet port always water sealed. Further, it is apparent that a number of other advantages are accomplished over the use of a structure as disclosed in the co-pending application or 10 devices of a similar nature contained in the art, where our improved form of carbonator is installed.

While we have illustrated and described only one specific form and specific mounting 15 for the invention, it will be understood that the position of mounting of the device might be reversed, and it will further be understood that a number of changes and modifications might be resorted to in the form and 20 arrangement of parts without departing from the spirit and scope of our invention, in view of which we wish to be limited only to such points as may be set forth in the claims.

25 We claim:—

1. A water carbonator comprising a casing structure having a water chamber therein, a mixing chamber within the casing having communication with the water chamber, 30 a water supply to said water chamber, a gas supply opening in the water chamber, and a valve structure mounted to simultaneously close the gas passage and close communication from the water chamber to the 35 mixing chamber.

2. A water carbonator comprising a casing structure having a water chamber therein, a mixing chamber within the casing having communication with the water chamber, a 40 water supply to said water chamber, a gas supply opening in the water chamber, a valve structure mounted to simultaneously close the gas passage and close communication from the water chamber to the mixing 45 chamber, and means located within the mixing chamber to agitate the water and gas to obtain a proper mixture thereof.

3. A water carbonator including a casing structure having a water chamber therein, a 50 mixing chamber within the casing, a water supply opening into the water chamber, a gas supply also opening into the water chamber, a valve structure constructed and mounted to simultaneously form a closure for the 55 gas passage and to stop communication from the water chamber to the mixing chamber, means to normally resiliently urge the valve to the closed position, and mixing means carried by the valve to be operated by the 60 pressure of air and gas flowing around the valve from the water chamber to the mixing chamber and to accomplish mixing of the same within said last mentioned chamber.

4. A water carbonator comprising a base

block having a water chamber therein, a 65 member connected with said base block to form a mixing chamber in communication with the water chamber, a water supply passage communicating with the water chamber at one side thereof, a gas supply 70 passage opening into the water chamber at one end, a sleeve mounted within the water chamber around the gas supply passage to conduct the gas to be discharged 75 into the water chamber adjacent the opening of the water supply passage, and a valve structure mounted to simultaneously close the gas passage and close communication from the water chamber to the mixing chamber.

5. A water carbonator comprising a base block having a water chamber therein, a member connected with said base block to form a mixing chamber in communication with the water chamber, a water supply passage 80 communicating with the water chamber at one side thereof, a gas supply passage opening into the water chamber at one end, a sleeve mounted within the water chamber around the gas supply passage to conduct the 85 gas to be discharged into the water chamber adjacent the opening of the water supply passage, a valve structure mounted to simultaneously close the gas passage and close communication from the water chamber to 90 the mixing chamber, and means located within the mixing chamber to be actuated by the flow of fluid around the valve to agitate the contents of the mixing chamber.

6. A water carbonator comprising a base 100 block having a water chamber therein, a member connected with said base block to form a mixing chamber in communication with the water chamber, a water supply passage 105 communicating with the water chamber at one side thereof, a gas supply passage opening into the water chamber at one end, a sleeve mounted within the water chamber around the gas supply passage to conduct the gas to be discharged 110 into the water chamber adjacent the opening of the water supply passage, a valve structure mounted to simultaneously close the gas passage and close communication from the water chamber to the mixing chamber, and means arranged in connection with the valve structure to normally urge the same to be resiliently held in a closed position.

7. A water carbonator comprising a base block having a water chamber therein, a 120 member connected with said base block to form a mixing chamber in communication with the water chamber, a water supply passage communicating with the water chamber at one side thereof, a gas supply passage 125 opening into the water chamber at one side, a sleeve mounted within the water chamber around the gas supply passage to conduct the

gas to be discharged into the water chamber adjacent the opening of the water supply passage, a valve structure mounted to simultaneously close the gas passage and close communication from the water chamber to the mixing chamber, and a valve to control and cut off the supply of fluid through the gas supply passage.

Copies of this patent may be obtained for five cents each, by addressing the "Commissioner of Patents, Washington, D. C."
